UNITED STATES PATENT OFFICE.

DANIEL W. HOGE, OF CHICAGO, ILLINOIS, ASSIGNOR, BY MESNE ASSIGNMENTS, TO
BASH OIL AND REFINING COMPANY, OF CHICAGO, ILLINOIS, A CORPORATION OF
DELAWARE.

APPARATUS FOR TREATING PETROLEUM VAPOR.

1,418,375.

Specification of Letters Patent. Patented June 6, 1922.

Application filed June 14, 1917. Serial No. 174,696.

To all whom it may concern:

Be it known that I, DANIEL W. HOGE, a citizen of the United States, residing at Chicago, in the county of Cook and State 5 of Illinois, have invented certain new and useful Improvements in Apparatus for Treating Petroleum Vapor, of which the following is a specification.

This invention relates to an apparatus for 10 treating petroleum vapor to increase the yield therefrom of distillate commercially known as gasoline.

It is the object of my invention to provide an apparatus wherein petroleum vapor may 15 be subjected in a reaction zone of relatively great length and small cross-sectional area to a uniform high temperature at a low pressure whereby the higher boiling point compounds in the vapor are broken down 20 into compounds having relatively low boiling points, so that the condensate corresponds closely in composition to natural gasoline.

A further object of my invention is the 25 provision of an apparatus which will successfully withstand the high heat essential to the success of the method and from which the portion constituting the reaction zone may be readily withdrawn for cleaning or 30 repairs.

Further objects and advantages of my invention will be apparent as it is better understood by reference to the following specification when read in connection with 35 the accompanying drawing, illustrating the preferred embodiment thereof, in which—

Fig. 1 is a vertical longitudinal section through the apparatus;

Fig. 2 is a transverse section through the 40 apparatus; and

Fig. 3 is a view in perspective of the receptacle for the bath of molten metal.

Referring to the drawing, 5 indicates a furnace structure of brickwork held together 45 by buck-stays 6 and tie-rods 7. The chamber within the furnace is divided medially by a supporting wall 8 on either side of which oil burners 9 or other suitable heating means are disposed. Above the burners 50 9 a baffle 10 extends entirely across the chamber, being supported on the side walls and on the supporting wall 8. The baffle 10 is provided with openings 11 at the end thereof opposite the burners 9 and on either side 55 of its medial line. Above and spaced from

the baffle 10 oppositely disposed baffles 12 are supported on the side walls and extend nearly across the furnace chamber. Openings are, however, provided, which openings being at the end of the chamber opposite the 60 openings 11 provide a zigzag passage for the products of combustion upwardly through the chamber; and a flue 31 for the escape of furnace gases may be provided in any desirable location in the wall of the furnace. 65

A receptacle 13 is mounted on the baffle 10 above the supporting wall 8 and is adapted to contain a quantity of lead or other suitable metal which is maintained in a molten condition and at a high temperature by means of the heat generated by the burners 9. The receptacle 13 comprises side and end walls and a bottom, and is constructed of sheet steel, the edges of the sheets being welded at the corners of the receptacle. 70 The receptacle is relatively narrow as compared with its depth and length and is supported within the furnace chamber by means of angle irons 14 riveted to the upper edges of the sides and ends of the receptacle and resting on the top of the furnace structure. Preferably a flaring mouth is provided at the top of the receptacle by riveting plates 15 thereto and to each other as clearly shown in Fig. 3. 75

Within the receptacle 13 I provide a tortuous passage through which the vapor is passed out of contact with the molten metal. This is best accomplished by providing headers 16 and 17, the former having legs 80 18 adapted to rest on the bottom of the receptacle 13. The headers are each provided with a plurality of chambers 19 separated by division walls 20. An inlet and an outlet opening to each chamber is provided in the 85 walls of the headers and pipes 21 connect the opposite openings. Opposite the ends of each of the pipes 21 the headers 16 and 17 are provided with threaded plugs 22 and 23 which, when removed, permit the insertion of a suitable instrument through the device to clear out accumulations of solid matter such for example as carbon which is invariably deposited during the operation 90 of the apparatus. Before the plugs 22 and 105 23 are removed the headers 16 and 17 with the pipes 21 are withdrawn from the receptacle 13. The flared mouthpiece serves to drain any molten metal adhering to the headers and pipes back into the receptacle. 110

Pipes 24 and 25 are connected, respectively, to the header 17 at the opposite ends thereof, the former serving to conduct the vapor from any suitable still into the apparatus 5 and the latter serving to deliver the product to a suitable condenser.

In employing my apparatus the crude oil is first distilled according to the usual method to remove the lighter fractions including the gasoline, or residues such as fuel or gas oils may be used. The residues are heated in a still to a temperate sufficient to volatilize the oil and the vapor is conducted through the pipe 24 to the apparatus 10 scribed and allowed to pass through the reaction zone within the pipes 21 at a pressure preferably not exceeding sixteen ounces. The temperature of the lead bath surrounding the pipes is preferably maintained at 15 between 900° and 1100° F., but it may vary between 750° and 1250° F.

The vapor, when subjected to this temperature and under conditions which permit the major portion of the vapor to contact with the walls of the pipes 21, is broken up or cracked to form compounds analogous to those present in natural gasoline and when the vapors are condensed they yield a liquid in every respect similar to gasoline 25 obtained from the lighter fractions of crude oil. The gasoline recovered is refined in the usual manner and is then ready for the market.

My apparatus is so constructed that the 30 weight of the molten lead is easily supported without danger of buckling the plates. By welding the edges of the plates I insure tight joints through which the lead can not possibly escape. By providing for the removal 35 of the headers and connecting pipes I am enabled to substitute another set of pipes while those previously in use are being cleaned, thus insuring continuous operation 40 of the apparatus. Accumulations of carbon 45 are readily removed from the pipes by removing the plugs 22 and 23 and inserting a suitable cleaning tool.

Various changes may be made in the details of the apparatus as above described 50 without departing from the spirit and scope of the invention or sacrificing any of its material advantages, the form hereinbefore described being merely the preferred embodiment thereof.

55 I claim:

1. An apparatus for treating petroleum vapor to obtain gasoline comprising a receptacle containing a bath of molten metal, bodily removable means in said receptacle 60 consisting of a plurality of independent straight sections connected in pairs alternately at their ends to form a continuous conduit for the vapor, and means for heating said bath.

65 2. An apparatus for treating petroleum

vapor comprising a receptacle for a bath of molten metal, bodily removable means in said receptacle forming a continuous conduit for the vapor, said conduit being divided into a plurality of independent 70 straight sections, means permitting access to the interior of said sections, and means for heating said bath.

3. An apparatus for treating petroleum vapor to obtain gasoline comprising a receptacle containing a bath of molten metal, bodily removable means in said receptacle including a pair of oppositely disposed headers, each having a plurality of independent chambers, and a plurality of 75 straight pipes connecting the chambers of the respective headers to form a continuous conduit for the vapor, and means for heating said bath.

4. An apparatus for treating petroleum vapor comprising a receptacle for a bath of molten metal, bodily removable means in said receptacle including a pair of oppositely disposed chambered headers and a plurality of straight pipes connecting the 80 chambers of the respective headers, removable plugs in said headers permitting access to the interior of said pipes, and means for heating said bath.

5. An apparatus for treating petroleum vapor to obtain gasoline, comprising a conduit for the vapor under treatment, said conduit having relatively great length with respect to its cross-sectional area and provided with means to frequently and abruptly 95 change the direction of the flow of vapor through said conduit, and means for heating the walls of the conduit to a temperature sufficiently high to crack the vapors into gasoline comprising a receptacle closed at 100 its bottom, sides and ends and containing a bath of molten metal submerging said conduit.

6. An apparatus for treating petroleum vapor to obtain gasoline, comprising a vertically disposed conduit for the vapor under treatment, said conduit having relatively 105 great length with respect to its cross-sectional area and provided with a plurality of abrupt return bends constituting means to 110 frequently and abruptly change the direction of flow of vapor through the conduit, and means for heating the walls of the conduit to a temperature sufficiently high to crack the vapors into gasoline comprising 115 a receptacle closed at its bottom, sides and ends and containing a bath of molten metal submerging said conduit.

7. An apparatus for treating petroleum vapor to obtain gasoline comprising an unobstructed conduit for the vapor under treatment, said conduit having relatively 120 great length with respect to its cross-sectional area and provided with a plurality of vertical sections connected by abrupt re- 125

- turn bends constituting means to cause the vapor to frequently and abruptly change its direction of flow through said conduit, and means for maintaining the conduit a 5 temperature sufficiently high to crack the vapors into gasoline comprising a receptacle closed at its bottom, sides and ends and containing a bath of molten metal submerging said conduit.
- 10 8. An apparatus for treating petroleum vapor comprising a vertically disposed receptacle for a bath of molten metal, the width of said receptacle being slight as compared with its length and depth, means in 15 said receptacle forming a continuous conduit for the vapor including a pair of oppositely disposed chambered headers located one above the other and a plurality of vertically arranged straight pipes connecting the 20 chambers of the respective headers, and means for heating said bath.
9. An apparatus for treating petroleum vapor to obtain gasoline comprising a vertically disposed receptacle containing a bath 25 of molten metal, the width of said receptacle being slight as compared with its length and depth, means in said receptacle including a pair of oppositely disposed chambered headers, one of said headers being supported on 30 the bottom of said receptacle and the other header being located near the top of the receptacle, and a plurality of straight vertically disposed pipes connecting the chambers of the respective headers to form a continuous 35 conduit for the vapor, and means for heating said bath.
10. An apparatus for treating petroleum vapor comprising a vertically disposed receptacle for a bath of molten metal, the width of said receptacle being slight as compared with its length and depth, means in 40 said receptacle forming a continuous conduit for the vapor including a pair of oppositely disposed chambered headers, one of said headers being supported on the bottom of said receptacle, a plurality of straight 45 vertically disposed pipes connecting the chambers of the respective headers, plugs in said headers adapted upon removal to give access to the interior of said pipes, and means for heating said bath.
11. An apparatus for treating petroleum vapor to obtain gasoline comprising a furnace, means for supplying heated combustion 55 products thereto, a receptacle containing molten metal within said furnace, baffle walls in said furnace to cause the products of combustion to travel back and forth in contact with said receptacle, and removable 60 means in said receptacle forming a continuous conduit for the vapor of relatively small cross-sectional area and great length, said conduit having a plurality of abrupt return bends.
- 65 12. An apparatus for treating petroleum vapor to obtain gasoline comprising a furnace, means for supplying heated combustion products thereto, a receptacle containing molten metal within said furnace, baffle walls in said furnace to cause the products of combustion to travel back and forth in contact with said receptacle, and removable means in said receptacle forming a continuous conduit for the vapor of relatively small cross-sectional area and great length, including a pair of oppositely disposed chambered headers and a plurality of straight pipes connecting the chambers of the respective headers.
13. An apparatus for treating petroleum vapor to obtain gasoline comprising a furnace, means for supplying heated combustion products thereto, a receptacle containing molten metal within said furnace, baffle walls in said furnace to cause the products of combustion to travel back and forth in contact with said receptacle, and removable means in said receptacle forming a continuous conduit for the vapor of relatively small cross-sectional area and great length, including a pair of oppositely disposed chambered headers, a plurality of straight pipes connecting the chambers of the respective headers, and removable plugs in said headers to permit access to the interior of said pipes.
14. An apparatus for treating petroleum vapors to obtain gasoline comprising a furnace having therein a zigzag passage, means for supplying heated combustion products to said passage, a receptacle containing molten metal vertically arranged in said passage in the path of said combustion products, whereby the products of combustion are caused to travel back and forth in contact with said receptacle, and means in said receptacle forming a continuous conduit for said vapor, said means being loosely supported and readily removable from said receptacle and provided with a plurality of abrupt return bends.
15. An apparatus for treating petroleum vapor to obtain gasoline comprising a receptacle closed at its bottom, ends and sides and containing a bath of molten metal, and means submerged in said bath and forming a continuous conduit for the vapor and consisting of a plurality of substantially parallel straight sections and chambers connecting adjacent ends of successive sections.
16. An apparatus for treating petroleum vapor to obtain gasoline comprising a receptacle containing a bath of molten metal, and means submerged in said bath forming a continuous conduit for the vapor and consisting of a plurality of parallel straight vertical sections and a plurality of horizontal chambers disposed transversely to the direction of said sections and connecting the sections in pairs alternately at their ends.

17. An apparatus for treating petroleum vapor to obtain gasoline comprising a receptacle containing a bath of molten metal, and means in said receptacle forming a continuous conduit for the vapor and consisting of a plurality of parallel straight sections in upright position, a series of independent chambers arranged in alinement above the sections, and a series of independent chambers arranged in alinement below the sections, said chambers connecting the sections in pairs alternately at their ends.
